SUNSCREENING DIHYDROXY-DIPHENYL-SULFONE DERIVATIVES

Charles A. Fetscher, Short Hills, and Stanley Lipowski, Newark, N.J., assignors to Nopco Chemical Company, Newark, N.J., a corporation of New Jersey

Filed Mar. 18, 1960, Ser. No. 15,880
11 Claims. (Cl. 167—90)

This invention relates to cosmetic preparations useful for protecting the skin against sunburn. More particularly, this invention relates to cosmetic preparations which protect the skin against burning when exposed to ultraviolet light radiation while at the same time permitting tanning of the skin.

It is known that ultraviolet radiation is responsible for both tanning and burning of the skin. This is because the portion of actinic radiation designated as ultraviolet light radiation actually is a distribution of radiation energy varying in wave length from 2800 Å. to 4000 Å. Within this range, the radiation of wave lengths of between 2800 Å. and 3150 Å., referred to as short wave ultraviolet radiation, is largely responsible for sunburn or erythema which is harmful to the skin. On the other hand, radiation having wave lengths between 3150 Å. and 3650 Å., referred to as long wave ultraviolet radiation, brings about healthful tanning with very little erythema effect. Hence, to permit successful tanning of the skin, a number of cosmetic preparations have been developed for the purpose of filtering out or screening out harmful short-wave ultraviolet radiation. However, many of these compositions suffer from a number of disadvantages. For example, many of these compositions suffer from inadequate selectivity. That is, although they prevent erythema, they also prevent tanning. Also, many of these preparations undergo a chemical change of the active ingredient when applied to the skin and exposed to ultraviolet radiation and air. This is accompanied not only by reduced effectiveness of the preparation as a sun screen, but also by undesirable staining of the skin and clothing with the decomposition products.

Accordingly, it is an object of the present invention to prepare cosmetic preparations which when applied to the skin selectively filter out and render harmless the burning ultraviolet radiation of wave lengths between 2800 Å. and 3150 Å. while at the same time transmit the longer ultraviolet radiation of wave lengths in excess of 3150 Å. so that the skin can be successfully tanned without burning or erythema. It is a further object to prepare cosmetic preparations which are stable and non-staining when applied to the skin and exposed to ultraviolet radiation and air. Another object is to prepare cosmetic preparations which also do not lose their effectiveness when exposed to ultraviolet radiation for relatively long periods of time. A still further object is to provide a method for obtaining a sun tan without sunburn. Other objects will become apparent from the detailed description given herein. It is intended however that the detailed description and specific examples do not limit the invention but merely indicate preferred embodiments thereof since various changes and modifications within the scope of the invention will become apparent to those skilled in the art.

We have unexpectedly discovered that the above and as well as other objects have been successfully achieved by means of cosmetic preparations of the nature of sun tan lotions, creams, oils and the like which contain as the effective ingredient alkyl and halogen derivatives of 2,2' dihydroxy diphenyl sulfone. It is known according to Patent No. 2,874,090, Klein, February 17, 1959; Patent No. 2,880,140, de Navarre, March 31, 1959, as well as others, that cosmetic preparations which contain as their effective ingredients compounds which have as resonating

2

structures amide, amino, carboxyl, carbonyl, nitro and sulfonic acid groups do exhibit selectivity in their ultraviolet absorption-transmission properties. However, it was most unexpected to discover that the compounds of the present invention very completely absorbed the short wave length ultraviolet radiation while at the same time transmitted the longer wave lengths in the absence of any of the above enumerated resonating structures. It was also unexpected to find that these compounds were extremely stable during exposure to ultraviolet radiation and air.

Our class of 2,2' dihydroxy diphenyl sulfones are represented by the following structure, viz:

15

20

wherein R can be halogen, or straight or branched chain saturated aliphatic hydrocarbon substituents having from one to five carbon atoms and R' can be hydrogen, halogen or straight or branched chain saturated aliphatic hydrocarbon substituents having from one to five carbon atoms. The aliphatic hydrocarbon substituents can have a greater chain length than indicated above. However, the increase in carbon chain length tends to dilute the absorbing function of the sulfone. Useful halogens are chlorine and bromine while useful straight and branched chain saturated aliphatic hydrocarbon substituents are, e.g., methyl, ethyl, propyl, isopropyl, butyl, isobutyl, amyl and sec. amyl. Exemplary of these 2,2' dihydroxy diphenyl sulfones are:

- 2,2' dihydroxy 5,5' dimethyl diphenyl sulfone
2,2' dihydroxy 5,5', 6,6' tetramethyl diphenyl sulfone
2,2' dihydroxy 4,4', 5,5' tetramethyl diphenyl sulfone
40 2,2' dihydroxy 5,5' diethyl diphenyl sulfone
2,2' dihydroxy 5,5' diisopropyl diphenyl sulfone
2,2' dihydroxy 5,5' tertiary butyl diphenyl sulfone
2,2' dihydroxy 5,5' di sec. amyl diphenyl sulfone
2,2' dihydroxy 5,5' dichloro diphenyl sulfone

45 In general, these 2,2' dihydroxy diphenyl sulfones can be prepared by reacting approximately two mols of a phenol having the formula

50

55

wherein R and R' have the same designations heretofore given, with approximately one mol of sulfuric acid. Useful phenols are p-cresol; p-chlorophenol; 3,4-dimethyl phenol, etc. The phenol and sulfuric acid, along with a solvent such as monochlorobenzene, are charged into a reaction kettle and refluxed. Enough solvent is kept in the system to maintain a good reflux. The amount of solvent necessary varies with the volume and shape of the equipment used and is adjusted according to conditions of operation. After about two mols of water have been removed azeotropically during reflux, the reaction mass is cooled down, more water added and the solvent removed azeotropically. The remaining material is washed with water at elevated temperatures. The water separates very easily as the upper layer and is easily removed by decantation. Then methanol or any other solvent is added which

dissolves the resinous by-products formed during the reaction, but does not dissolve the sulfone. In this manner, the sulfone separates out and when cooled down, the solution of resinous by-products is filtered off. The filtrate contains the solution of the resinous by-product while the sulfone stays behind. The sulfone is then washed and dried.

Useful 2,2' dihydroxy diphenyl sulfones can also be prepared by the oxidation of the appropriate 2,2' dihydroxy diphenyl sulfide. These sulfides are readily prepared by action of sulfur monochloride on the phenol.

The cosmetic preparations which contain these sulfones can be prepared in the following manner. The sulfone, or a mixture of sulfones can be admixed with a vehicle with agitation or with agitation and heating if necessary. Since these sulfones are powerful absorbers, the cosmetic preparation need contain only a small concentration of the sulfone in order to filter out most of the short-wave skin burning ultraviolet rays when the cosmetic preparation is applied topically as a thin film to the skin. Generally, the concentration of the sulfone or mixtures thereof in the cosmetic preparation can be from about 2% to about 8.5%, preferably about 4% to about 6% by weight of the total. Useful vehicles can be lotions, creams, oils, etc., i.e., any vehicle in which the active ingredient, i.e., the particular 2,2' dihydroxy diphenyl sulfone or mixtures thereof can be dissolved, admixed or dispersed. The vehicle thus serves as a carrier for the active ingredient so that it can be uniformly applied in small quantities over the desired areas of skin. Thus, the active ingredient can be dissolved in a water-ethanol solution within the proportions heretofore given. Alternatively, the active ingredient can be incorporated into any well known cosmetic base within the aforesaid proportions. Such bases can contain mineral oil, glycerine, lanolin, fatty acids, fatty acid esters, emulsifiers where needed, gums, etc. Ancillary ingredients such as colors, perfumes and preservatives can be present in small amounts, i.e., generally less than about 1% by weight of the total composition.

The first four examples are directed to the preparation of 2,2' dihydroxy diphenyl sulfones within the scope of this invention. In all of the examples, all parts are parts by weight unless otherwise indicated.

EXAMPLE I

2,2' dihydroxy 5,5' dimethyl diphenyl sulfone

216 parts of p-cresol, 100 parts of sulfuric acid (98%) and 50 parts of monochlorobenzene were charged into a reaction kettle. The resulting mass was stirred and heated until refluxing started. The vapor mixture leaving the kettle which contained water and monochloro benzene was condensed and allowed to settle. The water layer separated from the chlorobenzene layer and the latter was returned to the reaction kettle. Refluxing started at a temperature of about 140° C. after which the temperature was gradually raised to 180° C. Additional monochlorobenzene was added as needed to maintain a good reflux. After 32 parts of water were removed azeotropically from the reaction mass, the reaction mass was cooled down to 120° C. Fifty parts of water were then added and the solvent boiled off azeotropically. The reaction mass developed into an orange colored paste which was washed three times with 200 parts of water, each time at 60° C. The wash water separated very easily as the upper layer and was easily removed by decantation from the reaction mass. 250 parts of methanol were then added to the washed paste. The resin formed during the reaction dissolved in the methanol forming a green-brown colored solution while the sulfone separated from the solution as a cream powder. After cooling down to 8° to 10° C. the material was filtered and washed with methanol until the filtrate was clear, i.e., water-white. The sulfone was dried at 105° C. The product which was 2,2' dihydroxy 5,5'

dimethyl diphenyl sulfone was a light cream colored solid having a sharp melting point at 205° C. A yield of 34% of the theoretical was obtained.

EXAMPLE II

2,2' dihydroxy 5,5' dichloro diphenyl sulfone

257 parts of p-chlorophenol, 100 parts of sulfuric acid (98%) and 60 parts of monochlorobenzene were mixed together and heated with stirring. The water formed during the reaction was removed azeotropically in the same manner as in Example I. However, the temperature was raised gradually to 200° C. After 34 parts of water were removed from the reaction mass, all of the chlorobenzene which distilled over with the water was returned to the reaction vessel and 40 parts more of chlorobenzene were added. The reaction mass was cooled down to 20° C. and allowed to stand overnight during which time crystallization occurred. The crystalline material was filtered, washed with chlorobenzene and then with hot water and finally dried at 105° C. The product which was 2,2' dihydroxy 5,5' dichloro diphenyl sulfone was a white solid, having a melting point of 188° to 190° C. The yield was 48% of theoretical.

EXAMPLE III

2,2' dihydroxy 4,4',5,5' tetramethyl diphenyl sulfone

244 parts of 3,4 dimethylphenol were melted at 70° C. and 100 parts of sulfuric acid (96%) were added. The temperature was allowed to rise to 100° C. and kept at 100° C. for 15 minutes. The temperature was again raised, this time to 120° C., and kept for 15 minutes at 120° C. 100 parts of monochlorobenzene were then added to the reaction mass and the temperature raised gradually to 185° C. The water formed during reaction was removed azeotropically. After 32 parts of water were removed, the reaction mass was cooled down to 120° C., water added and the solvent removed azeotropically. Some unreacted 3,4 dimethyl phenol distilled over with the water-chlorobenzene vapors. The water remaining in the reaction vessel was siphoned off and the resulting red reaction mass was dissolved in 750 parts of methanol. This solution was then cooled down to 0° C. The sulfone separated and was filtered off, washed with cold methanol and dried under vacuum. The product which was 2,2' dihydroxy 4,4',5,5' tetramethyl diphenyl sulfone was a solid having an off-white color and having a melting point of 238° C. to 240° C. A yield of 40% of theoretical was obtained.

EXAMPLE IV

2,2' dihydroxy 5,5' dibutyl diphenyl sulfone

300 parts of p-tertiary butyl phenol were dissolved in 750 parts of carbon disulfide at reflux temperature. After the addition was completed, the resulting solution was cooled down to 20° C. and 135 parts of sulfur monochloride were slowly added while maintaining the temperature at 20° to 25° C. by cooling the reaction mass. During the addition, heavy fumes of hydrogen chloride escaped. After all of the sulfur monochloride was added, the reaction mass was heated and refluxed at about 50° C. for 30 minutes. In this manner, 2,2' dihydroxy 5,5' dibutyl diphenyl sulfide was formed. Thereafter, the carbon disulfide was removed by vacuum distillation. The 2,2' dihydroxy 5,5' dibutyl diphenyl sulfide was then dropped into cold water. After the water was decanted off, the sulfide was washed twice with water, taken up with ether, dried with sodium sulfate and finally the ether removed by evaporation. The sulfide was then dissolved in 750 parts of acetic acid after which 160 parts of hydrogen peroxide (50% by weight aqueous solution) were slowly added to the solution while using intermediate cooling to maintain the temperature at 90° to 95° C. The resulting product was dropped into cold water, taken up with ether, dried with sodium sulfate and finally the

ether evaporated in vacuum. The product which was 2,2' dihydroxy 5,5' dibutyl diphenyl sulfone was a heavy yellow syrup which solidified at room temperature. A yield of 50% of theoretical was obtained.

EXAMPLE V

A 0.004% by weight solution of 2,2' dihydroxy 5,5' dichloro diphenyl sulfone in isopropanol was prepared and the ultraviolet spectra of the solution was determined and recorded with a Beckman Model DU quartz spectrophotometer. The accompanying drawing reproduces the curve thus obtained. As the curve indicates, excellent absorption of the burning rays of the ultraviolet was achieved, especially in the range of 3000 A. which is the range responsible for maximum burning or erythema of the skin. Very little absorption of the longer rays of the ultraviolet occurred. These rays tan without burning.

EXAMPLE VI

A 0.004% by weight solution of 2,2' dihydroxy 5,5' dimethyl diphenyl sulfone in isopropanol was prepared and the ultraviolet spectra of the solution was determined and recorded with a Beckman Model DU quartz spectrophotometer. The resulting curve was almost the same as that obtained in Example V. The curve clearly demonstrated the excellent selectivity of this material, i.e., it very excellently absorbs the short ultraviolet radiation which is responsible for burning or erythema of the skin while at the same time it transmits the longer ultraviolet rays which bring about tanning without burning.

EXAMPLE VII

In this example, the compounds of Examples I, II and III were made up into dilute solutions in isopropanol as the solvent and the percent transmission of the ultraviolet as a function of wave length was determined. The percent transmission of the total amount of incident erythema energy and the percent transmission of the total amount of incident tanning energy was determined in the manner disclosed by Kreps in "Proceedings of the Scientific Section of the Toilet Goods Association," No. 23, May 1955. The data thus obtained are set forth as follows:

Sulfone from—	Conce. (percent weight)	Percent trans- mission of total incident erythema energy	Percent trans- mission of total incident tanning energy
Ex. I.....	4.5	9.15	91.0
Ex. II.....	5.5	8.45	89.0
Ex. III.....	8.3	7.50	85.0

The above data clearly indicate that the sunscreen compositions of the present invention are highly effective. They afford good protection against erythema by absorbing a large percentage of the undesirable burning rays while at the same time permit optimum tanning by transmitting a large percentage of the desirable tanning rays.

EXAMPLE VIII

In this example, several subjects were exposed to ultraviolet light radiation and the effectiveness of the sulfone determined. The procedure was as follows.

A solution of 5.5 grams of 2,2' dihydroxy 5,5' dimethyl diphenyl sulfone in 94.5 gm. of ethyl alcohol (95%) was applied to the underside of the right forearm of six subjects in an area approximately 1" x 3". Contiguous areas were protected by application of surgical tape. The treated areas were exposed to the radiation of a Hanovia quartz ultraviolet lamp for exactly 14 minutes. The distance from the exposed surface of the arm to the burner was 12" and the radiation was filtered through a plate of Corex D glass. Under these conditions, a minimum perceptible erythema is produced on the average in about one minute when the skin is not protected. The following evaluations were made after 24 hours.

Subject	Complexion	2,2' dihydroxy 5,5' dimethyl diphenyl sulfone
5 Male.....	Brunette.....	No erythema.
Do.....	Light brunette.....	Do.
Do.....	Brunette.....	Do.
Do.....	do.....	Do.
Female.....	Light brunette.....	Do.
Do.....	Blonde.....	Do.

10 The following three examples illustrate several cosmetic preparations which contain various sulfones. Each of these preparations was found to protect the skin from sunburn when applied to the skin and the thus treated skin exposed to strong sunlight for at least one hour. No staining of the skin or of adjacent clothing was observed.

EXAMPLE IX

	Percent by wt.
20 Ethanol (95%)	50
Water	45
2,2' dihydroxy 5,5' dichloro diphenyl sulfone	5

25 The above ingredients were mixed together with stirring to form the finished product. A portion of the product was applied to the skin which was exposed to strong sunlight for at least one hour.

EXAMPLE X

	Percent by wt.
30 White mineral oil	20
Propylene glycol	5
Isopropyl myristate	5
Lanolin	1
35 Non-ionic emulsifier ¹	3
2,2' dihydroxy 5,5' dimethyl diphenyl sulfone	4
Water	62

40 ¹The reaction product of octyl phenol and eight mols of ethylene oxide.

45 All of the materials except the water were mixed together and heated to 70° C. Then the resulting mixture was added to the water which was separately heated to 70° C. Blending with vigorous agitation was carried out to form a stable emulsion. A portion of the product was then applied to the skin which was exposed to strong sunlight for at least one hour.

EXAMPLE XI

	Percent by wt.
50 Stearic acid	5
Lanolin	10
Mineral oil	28
Ethanol (95%)	50
2,2' dihydroxy 5,5' dibutyl diphenyl sulfone	7

55 The above materials were mixed together and a portion of the resulting admixture was applied to the skin and exposed to strong sunlight for at least one hour.

60 As the foregoing has shown, outstanding sunscreen compositions have resulted from this invention. These compositions in a very excellent manner when applied to skin, permit tanning of the skin without undesirable erythema. These compositions are further characterized by their stability during use. That is, their effectiveness is not lost during exposure to air and sunlight. Also in view of their stability, these compositions do not stain the skin and adjacent clothing with decomposition products.

65 Having described our invention what we claim as new and desire to secure by Letters Patent is:

1. A method of screening out erythema ultraviolet light radiation having a wave length of between about 2800 A. and 3150 A. from skin while at the same time permitting tanning of the skin which comprises topically applying to human skin which is subject to sunburn a thin film of a

sunscreen composition containing (1) a sunscreen agent having the formula

wherein R is selected from the group consisting of halogen and straight and branched chain saturated aliphatic hydrocarbon substituents having from one to five carbon atoms and R' is selected from the group consisting of hydrogen, halogen and straight and branched chain saturated aliphatic hydrocarbon substituents having from one to five carbon atoms, said sunscreen agent further characterized by absorbing ultraviolet light radiation having a wave length between about 2800 Å. and 3150 Å. and (2) a pharmaceutically acceptable vehicle for said sunscreen agent, said sunscreen agent being present in said vehicle in an amount sufficient to screen out substantially all of said ultraviolet light radiation having a wave length of between about 2800 Å. and 3150 Å. when applied to the skin in a thin film.

2. The method of claim 1 in which said sunscreen composition contains said sunscreen agent in an amount of from about 2% to about 8.5% by weight of the total composition.

3. The method of claim 1 in which said sunscreen composition contains said sunscreen agent in an amount of from about 4% to about 6% by weight of the total composition.

4. The method of claim 3 in which said sunscreen agent is 2,2'dihydroxy 5,5'dimethyl diphenyl sulfone.

5. The method of claim 3 in which said sunscreen agent is 2,2'dihydroxy 5,5'dichloro diphenyl sulfone.

6. The method of claim 3 in which said sunscreen agent is 2,2'dihydroxy 4,4',5,5'tetramethyl diphenyl sulfone.

7. The method of claim 3 in which said sunscreen agent is 2,2'dihydroxy 5,5'dibutyl diphenyl sulfone.

8. The method of claim 3 in which said vehicle is a water-ethanol solution.

9. The method of claim 3 in which said vehicle is a cosmetic lotion.

10. The method of claim 3 in which said vehicle is a cream.

11. The method of claim 3 in which said vehicle is an oil.
